CLAIM

The ornamental design for plant stake apparatus, as shown and described.

DESCRIPTION

FIG. 1 is an operational isometric view of plant stake apparatus;

FIG. 2 is an isometric view of plant stake apparatus in extended position;

FIG. 3 is a front elevational view of plant stake apparatus in extended position;

FIG. 4 is a rear elevational view of plant stake apparatus in extended position;

FIG. 5 is a right elevational view of plant stake apparatus in extended position;

FIG. 6 is a left side elevational view of plant stake apparatus in extended position;

FIG. 7 is a top plan view of plant stake apparatus in extended position;

FIG. 8 is a bottom plan view of plant stake apparatus in extended position; and,

FIG. 9 is an isometric view of plant stake apparatus in retracted position.

The broken lines are included for the purpose of illustrating an environment of use and form no part of the claimed design.
